(57) **CLAIM**

The ornamental design for a stair tread, as shown and described.

DESCRIPTION

FIG. 1 is a perspective view of a first embodiment of my stair tread;

FIG. 2 is a front view;

FIG. 3 is a rear view;

FIG. 4 is a left side view;

FIG. 5 is a right side view;

FIG. 6 is an enlarged view of the encircled portion of FIG. 4;

FIG. 7 is a top view;

FIG. 8 is a bottom view;

FIG. 9 is a perspective view of a second version of the first embodiment of my stair tread;

FIG. 10 is a front view;

FIG. 11 is a rear view;

FIG. 12 is a left side view;

FIG. 13 is a right side view;

FIG. 14 is an enlarged view of the encircled portion of FIG. 12;

FIG. 15 is a top view;

FIG. 16 is a bottom view;

FIG. 17 is a perspective view of a second embodiment of my stair tread;

FIG. 18 is a front view;

FIG. 19 is a rear view;

FIG. 20 is a left side view;

FIG. 21 is a right side view;

FIG. 22 is an enlarged view of the encircled portion of FIG. 21;

FIG. 23 is a top view;

FIG. 24 is a bottom view;

FIG. 25 is a perspective view of a second version of the second embodiment of my stair tread;

FIG. 26 is a front view;

FIG. 27 is a rear view;

FIG. 28 is a left side view;

FIG. 29 is a right side view;

FIG. 30 is an enlarged view of the encircled portion of FIG. 29;

(Continued)

FIG. 31 is a top view; and,
FIG. 32 is a bottom view.
